CLAIM

The ornamental design for spectacles, as shown and described.

DESCRIPTION

FIG. 1 is a front top perspective view of spectacles showing our new design;

FIG. 2 is a rear bottom perspective view thereof;

FIG. 3 is a front view thereof;

FIG. 4 is a rear view thereof;

FIG. 5 is a left side view thereof;

FIG. 6 is a top view thereof;

FIG. 7 is a bottom view thereof;

FIG. 8 is an enlarged view of the encircled portion 8 indicated in FIG. 2; and,

FIG. 9 is an enlarged view of the encircled portion 9 indicated in FIG. 2.

The evenly dashed broken lines depict portions of the spectacles that form no part of the claimed design. The unevenly dashed broken lines demarcate enlarged views and form no part of the claimed design.
